UNITED STATES PATENT OFFICE.

ROBERT W. SNAPP, OF PETERSBURG, VIRGINIA, ASSIGNOR OF ONE-HALF TO CLIFFORD S. EDMUNDS, OF PETERSBURG, VIRGINIA.

CONNECTING DEVICE FOR SWITCH-POINTS.

1,230,047.

Specification of Letters Patent. Patented June 12, 1917.

Application filed October 23, 1915. Serial No. 57,543.

To all whom it may concern:

Be it known that I, ROBERT W. SNAPP, a citizen of the United States, residing at Petersburg, in the county of Dinwiddie and 5 State of Virginia, have invented certain new and useful Improvements in Connecting Devices for Switch-Points; and I do hereby declare the following to be a full, clear, and exact description of the invention, such as 10 will enable others skilled in the art to which it appertains to make and use the same.

The primary object of this invention is to provide a novel type of connecting device for connecting the main throwing rod and 15 front locking bar to the points of a switch operated by electrical or mechanical interlocking plants, and which connecting device can be adjusted with respect to the switch points so as to compensate for the expansion and contraction of the switch points in 20 order to prevent binding of the throwing rod and the locking bar.

Another object of the invention is to provide a connecting device for carrying out 25 the above object, which will also serve as a reinforcement for the adjacent switch point.

A further object of the invention is to provide a connecting device of the type 30 above referred to, which can be manufactured cheaply, which will be durable, efficient in operation and be conveniently applied to any type of switch point.

Other objects will appear and be better 35 understood from that embodiment of my invention of which the following is the specification, reference being had to the accompanying drawings forming a part thereof, in which—

40 Figure 1 is a top plan view of a main line and a switch therefor and showing the improved connecting device in operative position on the switch points.

Fig. 2 is a perspective of one of the connecting devices removed from the switch points.

Fig. 3 is an end view of the connecting device shown in Fig. 2.

Fig. 4 is a perspective view of a modified 50 form of connecting device.

Fig. 5 is a vertical transverse sectional view of the switch.

Referring to the drawings in detail, the letter A designates the rails of the main

line and B the movable switch points. Each 55 switch point has associated therewith a connecting device, designated as an entirety by the numeral 1. The connecting devices are identical in construction, and a detail description of one will suffice for both. 60

Each connecting device includes an elongated rectangular shaped plate 2 provided adjacent one end with a pair of elongated slots 3 and adjacent its opposite end with an elongated slot 4. The plate 2 is positioned 65 on the outer side of one of the switch points adjacent the free terminal thereof, and serves to reinforce the switch point and is held in position by means of bolts 5, which extend through the rails of the switch point 70 and are received by the slots 3 and 4 in the adjacent plate 2, the said bolts having their shanks threaded to accommodate locking nuts 6.

Each plate 2 has extending laterally and 75 outwardly therefrom a pair of arms 7 and 8. The arms 7 and 8 on each plate are of unequal length and lie in planes one above the other. The arm 7 is located at the outer end of the plate 2 and has its outer side edge 80 lying flush with the adjacent outer end of the plate 2 and includes an obtuse angle portion 9, having one arm 10 connected to the plate 2, the other arm designated 11 connected to a horizontally extending portion 85 12, which extends outwardly from the arm 11 and is provided adjacent its outer terminal with an opening 13. The plate 2 and the angular portion 9 of the arm 7, are further connected by an angular shaped flange 90 14 which serves to strengthen the arm 7 and reinforce the same at the point of juncture between the arm and the plate 2.

The arm 8 is located at a point between the slots 3, adjacent the inner end of the 95 plate 2 and is arranged in spaced relation to the inner end of the plate 2 and includes a downwardly inclined portion 15 and a horizontally disposed portion 16 carried by the lower end of the portion 15 and is of a 100 length considerably greater than the length of the horizontally disposed portion 12 of the arm 7 and lies in the plane above the plane of the said horizontally disposed portion 12 and is provided, adjacent its outer 105 end with an opening 17. The inclined portion 15 of the arm 8, is connected to the plate 2 by means of an angular shaped flange

18 which serves to strengthen the arm 8 and also reinforce the point of juncture between the arm 8 and the plate 2.

The arms 7—7 of the opposed plates 2—2 are connected to each other by means of a connecting rod 19 which has one end arranged in overlapping engagement with the horizontally disposed portion 12 of one of the arms 7 and has its outer end threaded 10 and received by an adjustable sleeve 20, one end of which is flat and overlies the horizontal portion 12 of the arm 7 on the other plate 2. The end of the rod 19 and the flattened end of the sleeve 20 are connected to 15 the arms 7 by pins 21. The connecting rod 19 is provided at a point intermediate of its ends with a laterally extending lug 22, to the outer terminal of which is connected a flattened end 23 of a sleeve 24 by means of a pin 25. The sleeve 24 receives one end of a locking bar 26, the opposite end of which extends beneath the rails and is provided with notches 27 for the reception of a locking element, not shown. The arms 8—8 of 20 the plate 2—2 have connection with each other by means of a connecting bar 28, the opposite ends of which extend beneath the portions 16 of the arms 8 and are provided with openings which register with the openings 17 in the portions 16 for the reception 25 of bolts 29. The bar 28 has one end extending beneath the stock rail of the switch to prevent upward movement of the switch points, as shown in Fig. 1 of the drawing. 30 By virtue of the fact that the portions 16 of the arms 8 lie in a plane above the portions 12 of the arms 7, the connecting rod 28 will be disposed in substantially the same horizontal plane as the connecting rod 19. 35 Associated with the connecting bar 28 is a bracket 30 which is located at a point intermediate of the ends of the bar 28 and is provided with a pair of laterally extending ears 31 which carry aligned threaded sleeves 32 40 for the reception of the threaded end 33 of a switch throwing rod 34 as shown in Fig. 1 of the drawings. By virtue of providing the plate 2—2 with the elongated slots 4 the plates can be moved longitudinally, in either 45 direction, on the switch points to compensate for the expansion and contraction of the switch points and prevent binding of the bar 26 and the rod 34 and insure of the accurate throwing and locking of the switch 50 points. In the modification shown in Fig. 4, the arm 8 includes a substantially horizontal portion 35, a vertical portion 36 depending from the outer end of the portion 35, and a horizontally disposed substantially 55 U-shaped frame 37 adapted to receive the adjacent end of the connecting bar 28 and has its sides arranged in superposed relation with each other and provided with aligned openings 38 for the reception of a bolt, which passes through the sides of the 60

frame 37 and through the adjacent end of the connecting rod 28. An angular shaped flange 39 extends along the horizontal portion 35 and the vertical portion 36 and has its opposite ends connected respectively to the plate 2 and to the upper side of the frame 37. The flange 39 serves to strengthen the arm and also to reinforce the points of juncture between the frame and the vertical portion 36 and the vertical portion and the horizontal portion 35 and between the latter portion and the plate 2.

By forming each of the connecting devices in one integral piece, the switch points will be reinforced at their free ends, and also the throwing rod and the lock bar will be simultaneously moved with the connection, thereby admitting of both rods receiving the same degree of adjustment.

From the foregoing description taken in connection with the accompanying drawings, it will be seen that the connecting device set forth will be durable, efficient in use and can readily be adjusted to compensate for the expansion and contraction of the rails of the switch, so as to prevent the locking bar and the switch throwing rod from binding in their bearings.

What is claimed is:

1. The combination with a pair of switch points and the connecting bars for the switch points, of plates adjustably mounted on the switch points, means for holding the plates in their adjusted position and means for connecting the plates to the connecting bars.

2. The combination with a pair of switch points and the connecting bars for the switch points, of plates carried by the points and each of the plates having a pair of laterally extending arms thereon, the arms forming each pair being arranged one above the other, and means for connecting the arms to the connecting bars.

3. A connecting device of the character described, comprising an elongated plate, arms extending outwardly from the plate and including an inclined portion and a horizontally disposed portion, and angular shaped ribs carried by the arms and connected to the plate.

4. A connecting device of the class described comprising an elongated plate having an elongated slot adjacent one end thereof and a pair of spaced slots adjacent the opposite end, an arm formed integral with the first mentioned end of the plate, and a second arm formed integral with the plate and located between the spaced slots at the second mentioned end of the plate and spaced from the said end.

5. A connecting device of the class described comprising a plate, laterally extending arms carried by the plate, a U-shaped frame carried by one of the arms,

and a flange formed on the last mentioned arm and coextensive therewith and having the opposite ends thereof integrally connected, respectively, to the plate and one side of the frame.

6. A connecting device of the class described comprising a plate, arms carried by the plate and extending laterally therefrom, one of the arms including an obtuse angular 10 shaped portion and a horizontally extend-

ing portion connected to the obtuse angular portion and the other arm including a downwardly inclined portion and a horizontally disposed portion.

In testimony whereof I affix my signature 15 in presence of two witnesses.

ROBERT W. SNAPP.
